UNITED STATES PATENT OFFICE.

NATHAN H. DAVIS, OF PHILADELPHIA, PENNSYLVANIA.

LID FOR JOURNAL-BOXES.

SPECIFICATION forming part of Letters Patent No. 431,254, dated July 1, 1890.

Application filed December 10, 1888. Serial No. 293,157. (No model.)

To all whom it may concern:

Be it known that I, NATHAN H. DAVIS, a citizen of the United States, residing in the city and county of Philadelphia, State of Pennsylvania, have invented a new and useful Improvement in Lids or Covers for Journal-Boxes, which improvement is fully set forth in the following specification and accompanying drawings.

10 My invention consists of a lid for a journal-box formed of wrought metal, whereby the same is light, inexpensive, strong, and durable.

It also consists of the construction of the lid with novel features, as will be hereinafter set forth and definitely claimed.

Figure 1 represents a perspective view of a lid for a journal-box embodying my invention. Fig. 2 represents a section on line $x-x$, Fig. 1. Fig. 3 represents an irregular section 20 on line $y-y$, Fig. 1, showing also part of the axial bolt or pivot and the spring thereon in dotted lines.

Similar letters and numerals of reference denote corresponding parts in the several figures.

Referring to the drawings, A represents a lid for a journal-box, the same being formed of wrought metal, having at one end a finger-piece 1, whereby it may be raised 30 from its axis, which is at the other end, the latter end having an opening 2 for the bolt or pivot on which the lid turns. The wall of the opening 2 is flanged in the present case in outward direction, the flange 3 being struck 35 or bent out and forming a lengthened bearing for the bolt or pivot and strengthening the wall of the opening 2. At or about the center of the lid is a concavity 4, formed by striking up or pressing the metal outwardly 40 and thereby forming a socket for the free projection of the inner end of the journal or axle thereinto. At the axial end of the lid above the opening 2 is a lip 5, which is struck or bent inwardly so as to overhang or over- 45 lap the top wall of the box at a place contiguous to said lip, the latter being of such length as to be in contact with the top of the box when the lid is fully drawn out against the spring.

50 It will be seen that when the lid is drawn outwardly or from the axle preparatory to

opening the same, as usual in such cases, its bottom wall clears the adjacent edge of the box, the lip 5 retaining its seat on the edge of the box with which it was primarily in contact, whereby the lid is prevented from falling, so that its lower edge is below the upper edge of the flange 6 on the box on which it rests when the lid is closed. The lid may now be thrown up or partially rotated 60 on the bolt or pivot in order to open the box, when the journal or axle is readily accessible. When the lid is dropped or lowered its descent is limited by the lip 5 striking its resting-place, after which the force of the spring 65 will push the lid inwardly or backwardly, and thus set the same in position.

The outward or inward motions of the lid are readily permitted, owing to the free connection of the lid with the bolt or pivot on 70 which it turns, the spring on said bolt or pin readily yielding when the lid is drawn outwardly, and exerting its pressure to hold the lid when in closed position.

I am aware that it is old to construct by 75 casting a metallic lid for a journal-box; but I am not aware that it is common to form the same of wrought metal, as herein claimed. It is also known to be old to form a lid for such purpose with a central concavity and 80 an opening at one end and a handle at the other; but I am not aware that it is old to form or construct one as herein described and claimed, wherein on an inclined or slanting portion of the upper edge thereof is formed 85 a rearwardly-projecting lip above the end opening, and the latter having extending from its walls a boss, giving an increased bearing for the connecting-bolt.

Having thus described my invention, what I 90 claim as new, and desire to secure by Letters Patent, is—

1. A lid or cover for a car-journal box constructed of struck-up wrought metal and having a flanged bearing or sleeve 3, to provide 95 a pivotal connection, substantially as described.

2. A lid or cover for a journal-box made of wrought metal and having a lip 5 and a flanged bearing or sleeve 3 struck from the 100 same in reverse directions, substantially as described.

3. A lid or cover for a journal-box made of wrought metal having a struck-up concave portion 4, to fit over the journal end, a lip 5, and a flanged bearing or sleeve 3, struck from the lid in reverse directions, substantially as described.
4. A lid or cover for a car-axle journal-box, consisting of a plate of wrought metal having a lip 5, and a bearing or sleeve 3 struck there-

from in reverse directions, a substantially to central convex swell 4 struck up from the plate, and a projection 1, by which the lid may be turned or raised on its axis, substantially as described.

NATHAN H. DAVIS.
